(57) **CLAIM**

The ornamental design for wheel, as shown and described.

DESCRIPTION

FIG. 1 is a right front perspective view of a wheel according to the present invention.

FIG. 2 is a front view of the wheel shown in FIG. 1; and, FIG. 3 is a side view thereof.

The broken line showing of the rear portion of the wheel, the bolt holes, the center hole, and the valve stem hole is included for the purpose of illustrating environment and forms no part of the claimed design.

1 Claim, 2 Drawing Sheets**FIG. 1**

FIG. 2

FIG. 3
